UNITED STATES PATENT OFFICE.

HERMANN JULIUS QUAMBUSCH, OF BECKACKER, NEAR LANGERFELD, GERMANY.

BRAIDING-MACHINE.

No. 861,897.

Specification of Letters Patent.

Patented July 30, 1907.

Application filed November 28, 1905. Serial No. 289,499.

To all whom it may concern:

Be it known that I, HERMANN JULIUS QUAMBUSCH, a subject of the Emperor of Germany, residing at Beckacker, near Langerfeld, in the Kingdom of 5 Prussia and German Empire, have invented new and useful Improvements in Braiding-Machines, of which the following is a specification.

In braiding and lace-making machines the crossed threads are "beaten up", that is to say, forced up to the 10 thread-collector, located at the place of plaiting or twisting, by a so-called "beater." Two groups of beaters have been provided for this purpose, working alternately, in such manner that the one beater-group holds the crossed threads it has beaten up at the 15 thread-collector, while the other group is about to beat up to the collector the crossed threads it has taken up. The beater-groups are actuated in the necessary manner by two eccentric tracks exercising a counter action. The defect of the method is, that the beater-edges which 20 seize the crossed threads strike against the thread-collector with increasing force, the more the limit of the stroke of the beaters deviates from the correct stroke, either owing to inexact adjustment of the parts operating the beaters or to wear and tear. Owing to the 25 beaters continually striking the collector, the beater edges which push the crossed threads before them gradually become blunt, and in time present a bur, which is injurious to the threads, since it causes them to fray and often even cuts them through. The thread- 30 collector itself moreover, becomes grooved owing to the repeated blows of the beaters, and these grooves, especially at the bottom edge of the collector, greatly obstruct regular working. Even the use of hardened steel beaters and a hardened collector does not really 35 obviate the defect, while other disadvantages attend the employment of such hardened parts, which, moreover, involve very considerable extra outlay. Another dis-advantage of the said method of operating the beaters is the intermittent action which is involved 40 by the tracks of the two eccentrics on change of the stroke. For this intermittent action results in a jerky motion of the beaters; and further-more, especially in view of the large number of beaters and the high speed of revolution of the eccentrics, severe shocks are 45 experienced in the machine, whereby proper operation of the mechanism is obstructed and the wear and tear of the parts greatly increased.

With the beater forming the subject of the present invention all these defects are entirely overcome by 50 providing mechanism of such description that the advance of the beater is effected by a spring up to a certain limit which is determined by a beater stop, while

the retreat of the beater is effected by means of a simple crank-motion, in such manner, that within one revolution, the half of one stroke is utilized for the rearward motion of each beater of the one group, and the half of the other stroke for the rearward motion of each beater of the second group. In this way the beaters, owing to the spring-pressure, are advanced toward the thread-collector, and the extent of their motion limited 55 by the stop which arrests them, in such manner that their end which holds the crossed threads exactly reaches the collector, without, however, striking the latter a hard blow. The reciprocation of the beaters is not intermittent, since in both directions they must 60 follow the always uniform strokes due to the rotation of the crank, in the advance owing to the spring, and in the retreat on account of the half-stroke. This method of operating the beaters also has the advantage of preventing the beater-ends from being jerked 65 aside.

My invention is illustrated in the accompanying drawings, in which

Figure 1 is a longitudinal section of the new beating-up device. Fig. 2 is a vertical section taken on the 75 line A—B of Fig. 1, the eccentric having made a half revolution. Fig. 3 is a fragmentary plan of Fig. 1.

The beaters *a* of the one group and the beaters *b* of the other group which, as is well known, are disposed alternately in radial position round the plaiting-point 80 and the thread collector *c*, are carried by supports *d*, which stand on a stationary plate *e*, secured to the tubular support *f*, located at the center of the machine. Each beater slides on a guide *g*, which is secured to the support *d* with capability of adjustment in the direction of the beater. This adjustment can, as the drawings show, be effected by the employment of an arm *g*₁, pivoted at the point *g*₂ and secured by means of a bolt *g*₄ passing through a curved slot *g*₃. Or the guide *g* itself may turn on a bolt and be adjustably mounted in a 90 slot. The corners of the guide *g* are suitably rounded, in order to admit of the unobstructed up and down motion of the free end of the beater. The guide *g* also serves as stop for the beater, the tail of which is bent round so as to grip the guide; the free end of the beater 95 can thus only advance under the influence of the spring *i* until the bent tail of the beater strikes the guide *g*. In view of the adjustability of the guide, the extent of advance of the beater toward the collector can be determined with the greatest exactitude. In view of 100 the stroke of the beater being a light and easy one, the guide may be made of vulcanite, lignum vitæ, or like material.

*h h*₁ is a bell crank lever with the limb *h* of which the

beater is connected. The beater is pressed toward the collector *c* by the spring *i*. In the particular construction shown in the drawing, the spring *i* presses against a rod *k*, connected at the opposite end to the lever-arm *h*.

5 On the central support *f* the sliding collar *l* is provided below the plate *e*, on which collar there rests the plate *m*, having apertures *m₁* through which pass the rods *n*, secured to the arms *h₁* of the levers *h* *h₁*. The plate *m* is connected, with the aid of rods *p*, with a

10 crank, or an eccentric *o* having a crank motion, so that on rotation of the eccentric, the plate *m* works uniformly up and down on the support *f*. The throw of the eccentric is so selected that half of it is sufficient for the beater-motion; and on the rods *n*, stops *n₁* are provided,

15 which stops, in the case of the rods *n* for the beaters *a* of the one group, are located above the plate *m*, and in the case of the rods of the beaters *b* of the other group, below the plate *m*. Thus on ascent of the plate *m*, the beaters *a* are retracted from the collector *c* directly the

20 plate strikes the stops *n₁* of the rods *n*; while on descent of the plate *m* a like retrogressive motion is imparted to the beaters *b*, when the plate strikes the stops *n₁* of the rods *n* lying below it. Since the motion of the beaters of the group *a* only takes place during the sec-

25 ond half of the upward stroke of the plate *m*, and the motion of the beater group *b* on the second half of the downward stroke, it is obvious that the beaters of both groups occupy their end positions alternately, so that they are at rest for a certain period also in the position

30 at the collector *c*. In this manner the crossed threads beaten up by one group are held at the collector, until the beaters from the other group have brought up their crossed threads to the collector.

For the purpose of insuring the free ends of the

35 beaters lateral guidance, they are passed between members *q* secured to stems or pins *q₁*, which serve at the same time as holders for the front part of the beaters, which pass through perforations or holes *q₂*. In order that the beater-ends, in addition to their for-

40 ward and back motion, may also move in such manner that at the commencement of their advance-motion they rise to the level of the plaiting-threads *r*, and on retreat descend below the threads, the pins *q₁* of the beater-group *a* are secured to a vertically reciprocating

45 plate *s*, and the pins of the other beater-group *b* to a plate *t*, which likewise reciprocates vertically, but independently of the plate *s*. In correspondence with the alternation of the forward and backward motion of the beater-groups therefore, there takes place also their

50 up and down motion. These motions are effected by means of cams *u* and *v*, on which rest the rods *u₁*, *v₁*, which engage the plates *t* and *s* respectively by means of forked grippers *t₁* *s₁*. Through the vertically reciprocating motion of the plates *s* and *t*, due to the rotation of the cams, it is obvious that the beaters, turning correspondingly on the guides *g*, will be given the necessary motion for bringing them into and out of the plaiting-threads.

Having thus described my invention, what I claim

60 is:—

1. In braid and lace making machines, thread beating mechanism, comprising in combination, a central support; a stationary plate secured thereto; radially disposed beater-guides carried by the stationary plate two groups of beat-

ers the advance of which is limited by the said guides; 65 springs continually forcing forward, means separate from the springs for retracting and means for depressing on their retrograde motion, the two beater-groups independently of each other; and crank mechanism imparting an up and down motion to the beater retracting-means and 70 beater depressing-means, in such manner that within one revolution the half of one stroke effects retraction of the one beater-group and the half of the other stroke the retraction of the other beater-group; all substantially as and for the purposes described.

2. In braid and lace making machines, thread beating mechanism, comprising in combination, a central support, a stationary plate secured thereto, radially disposed beater-guides carried by the plate and made adjustable in radial directions, two groups of beaters the advance of which is 80 limited by the said guides, means independent of one another for respectively forcing the beaters continuously forward and for intermittently retracting the beaters, and independent vertically movable guides for depressing the two beater-groups independently of each other, and crank 85 mechanism imparting an up and down motion to the beater retracting means and beater depressing means, in such manner that within one revolution the half of one stroke effects retraction of the one beater-group and the half of the other stroke the retraction of the other beater-group, 90 all substantially as and for the purpose described.

3. In braid and lace making machines, thread beating mechanism, comprising, in combination, a stationary central support; a stationary plate secured thereto; radially disposed uprights on the plate; beater guides pivotally 95 carried by the uprights and adjustable in radial direction; two groups of beaters the tails of which engage the said guides; a plate sliding on the central support below the said stationary plate; bell-crank levers pivoted to a stationary machine-part and having one limb connected to 100 the beaters, and means for continually forcing this limb inward, the other limb of said levers passing through the two said plates, the pendent limbs for the one beater-group having a stop located above the sliding plate, and the pendent limbs for the other beater-group having a stop 105 located below the said sliding plate; depressor-guides for the front beater-ends; disks separately carrying the depressors of the two beater-groups respectively and sliding independently on the said central support; and crank mechanism imparting an up and down motion to the sliding plate and the two sliding disks, in such manner that within one revolution the half of one stroke effects retraction of the one beater-group and the half of the other stroke the retraction of the other beater-group; all substantially as and for the purposes described.

4. In braiding and lace making machines, thread beating mechanism comprising a support with beater guides and beater actuating levers, said guides and levers being independent of one another, beaters engaged by the guides and levers, a reciprocating plate, and links connected to the 110 levers and respectively provided with oppositely located plate engaging points so that said levers are alternately actuated as the plate reciprocates.

5. In braiding and lace making machines, thread beating mechanism comprising beaters, guides about which said beaters are loosed to have their movement arrested thereby, levers for actuating the beaters, and springs made to engage the levers to permanently force or press the beater in one direction.

6. In braiding and lace making machines, thread beating mechanism comprising beaters, movable guides for the front ends of the beaters, and fixed guides at the rear of the beaters and made to arrest the latter.

7. In braiding and lace making machines, thread beating mechanism comprising beaters, movable guides for the beaters comprising members with perforated stems for guiding various parts of the beaters, actuating means for the guides, and stationary guides to arrest the beaters.

8. In braiding and lace making machines, thread beating mechanism comprising beaters, reciprocating guides for 140 the front parts of the beaters, and stationary arresting guides at the rear parts of the beaters, and about which the needles are hooked.

9. In braiding and lace making machines, thread beating mechanism comprising beaters and actuating mechanism therefor, combined with beater arresting guides and fixed supports on which the guides are adjustably mounted.
- 5 10. In braiding and lace making machines, beating mechanism comprising beaters and actuating mechanism therefor, combined with beater arresting guides, and fixed supports for the guides, said guides and supports having pin and slot connections for adjustably securing the guides.
- 10 11. In braiding and lace making machines, beating mechanism comprising beaters and guides, actuating levers for

the beaters, springs made to engage the levers for permanently forcing or pressing the needle in one direction, and an actuator for the levers for moving the beaters against the action of the springs.
